UNITED STATES PATENT OFFICE.

JOHN B. SMILEY, OF SOUTH OMAHA, NEBRASKA.

ELECTRIC OPEN-SWITCH AND STOP SIGNAL.

SPECIFICATION forming part of Letters Patent No. 785,026, dated March 14, 1905.

Application filed December 14, 1904. Serial No. 236,806.

To all whom it may concern:

Be it known that I, JOHN B. SMILEY, a citizen of the United States, and a resident of South Omaha, in the county of Douglas and 5 State of Nebraska, have invented a new and Improved Electric Open-Switch and Stop Signal, of which the following is a specification.

In the accompanying drawings I have shown in Figure 1 a top view of a rail system with 10 portions broken away equipped with my open-switch and stop signal. Fig. 2 shows a sectional detail of one of the contact details. Fig. 3 discloses a detail of the semaphore used in my invention, while Fig. 4 discloses a broken 15 portion of a locomotive, showing position of the alarm-bell and one of the contact-brushes as used in my invention.

My invention relates to an electric open-switch and stop signal, the aim being to provide a mechanism so arranged that whenever 20 a switch is open the train approaching the open switch will be notified by means of an audible alarm in the engineer's cab that the switch is open, as will also the train approaching from the opposite direction, so that whenever the switch is open the engines approaching the switch from both directions will receive an alarm, so that the engineers will be notified, and thereby cautioned.

30 In the accompanying drawings I have shown in Fig. 1 a plan view of a portion of a rail system provided with my signal apparatus. The rails A and A' are secured to suitable ties *a*, and at a suitable point I provide a projecting tie 23', to which the switch-stand 23 is secured, as shown. This switch-stand is provided with the usual rock-shaft 20, holder 21, and pendent operating-handle 22, adapted to be locked into the switch-stand, from which 35 extends an operating-bar 19, as disclosed, secured to the shifting ends B' and F of the split rails. These rails B' and F are connected by means of the bar C, which bar works through the housing D, and by means of a 40 pin 19' has its end secured to the rock-lever *c*, mounted upon the pivot-pin *o*, this rock-lever being provided with the contact-maker 3 in electrical connection by means of the conductor 8 with the contact-rail 1'. (Shown in Fig. 1.)

45 Between the rails A and A' are held two

sets of contact-rails—one set being 1 and 1', approaching the switch from one direction, while coming from an opposite direction are the contact-rails 2 and 2'. These rails are of like construction and, as shown in Fig. 2, are 55 provided with a base-stringer 18, upon which is placed suitable insulating material 17, supporting a wooden rail 16, to which wooden rails are secured the contact-rails 1, 1', 2, and 2'.

Held within the housing D by means of a 60 pin *p* is the electric terminal 4, from which extends the conductor 5, leading to the battery 6 within the housing, and extending from the opposite pole of the battery is a conductor 7, leading to the rail 1. Now these instrumentalities are so arranged that whenever the switch is open—that is, set for the siding, including the rails B and B', as is shown in Fig. 1—the bar C will bring into engagement the terminals 3 and 4, so that in this condition the rails 1 70 and 1' form electrical terminals.

The locomotives are provided with suitable electric alarm-bells 22, as shown in Fig. 4, of any suitable construction, from which bells extend two similar conductors 21, each leading 75 to a plate 20, from which extends a holder 19, holding a scraping-brush *v*, which brushes are adapted to work with an abrading effect upon the contact-rails, so that a locomotive equipped with two such brushes *v* would complete the circuit to ring the alarm 22, thus notifying the engineer approaching the switch of the fact that the switch was set and open—in other words, giving alarm to show that the track was not clear. Upon the opposite side 80 extending from the rail 2 is a conductor 9, leading to the battery 10, from which battery 10 extends the conductor 11, leading to the terminal 12, which terminal is adapted to be engaged by the contact-maker secured to the 85 semaphore *e*, working upon the pivot 40, as shown in Fig. 3, the semaphore *e* being operated by means of a suitable operating-chain *x*, the semaphore being secured to a suitable base E, as disclosed. Now when the switch 90 is open, as disclosed in Fig. 1, the train approaching from the direction so that the contact-rails 2 and 2' are engaged the bell within that locomotive will be rung, as the operator 95 will have set the semaphore *e* to complete the 100

circuit, the conductor 15 completing the circuit in being led to the contact-rail 2, so that the engines approaching this open switch from both sides are notified by means of the 5 audible alarm. In construction of my device as illustrated the contact-rails 1, 1', 2, and 2' will be kept clean and free of corrosion, as the brushes v will have a tendency to scrape these rails and keep them free from obstructions. 10 From this it will be noticed that I provide a device by means of which I notify the engineer in time to stop his train in approaching the open switch. The engineer failing to obey orders in passing a set semaphore is 15 likewise notified to stop by means of the ringing of his alarm-gong.

My invention is especially adapted to be used in connection with the railroad-tracks near to the stations.

20 Having thus described my said invention, what I claim as new, and desire to secure by United States Letters Patent, is—

The combination with a switch-provided

railway system, of two contact-rails positioned between the steel rails proper, a pivotally-held contact-making rock-lever, an electric conductor extending from said rock-lever to one of said intermediate contact-rails, a connecting-bar secured to the moving rail ends of the switch and being in engagement with 25 said contact-making rock-lever, an electrical terminal in circuit, said rock-lever being adapted to come in contact with said terminal, a conductor leading from said electrical terminal, and secured to the remaining contact- 30 rail, two pendent brushes secured to a suitable locomotive and adapted to come in contact with said contact-rails, and a suitable electric bell in circuit with said brushes.

In testimony whereof I affix my signature in 40 presence of two witnesses.

JOHN B. SMILEY.
